UNITED STATES PATENT OFFICE

171,286

SET OF CHESSMEN OR SIMILAR ARTICLE

Herman Ohme, Los Angeles, Calif.

Application March 16, 1953, Serial No. 24,034

Term of patent 14 years

(Cl. D34—5)

To all whom it may concern:

Be it known that I, Herman Ohme, a citizen of the United States, residing at Los Angeles, in the county of Los Angeles, and State of California, have invented a new, original, and ornamental Design for a Set of Chessmen or Similar Article, of which the following is a specification, reference being had to the accompanying drawings, forming a part thereof:

Figures 1, 2, 3, 4, 6 and 8 are side elevational views, respectively, of the Queen, King, Bishop, Knight, Castle and Pawn in a set of chessmen, showing my new design.

Figure 5 is a front elevational view of the Knight shown in Figure 4; and

Figure 7 is a fragmentary cross-sectional view of the Castle, taken on line 7—7 in Figure 6.

I claim:

The ornamental design for a set of chessmen or similar article, substantially as shown.

HERMAN OHME.
